UNITED STATES PATENT OFFICE.

RALPH M. LICKLEY, OF EAST CLEVELAND, OHIO.

DRIFTING-VALVE DEVICE FOR LOCOMOTIVES.

1,301,853.

Specification of Letters Patent. Patented Apr. 29, 1919.

Application filed February 17, 1916, Serial No. 78,872. Renewed February 23, 1917. Serial No. 150,622.

To all whom it may concern:

Be it known that I, RALPH M. LICKLEY, a citizen of the United States, and a resident of East Cleveland, in the county of Cuyahoga and State of Ohio, have invented a new and Improved Drifting-Valve Device for Locomotives, of which the following is a full, clear, and exact description.

The object of the invention is to provide a simple and efficient means of supplying a sufficient amount of saturated steam from the boiler of the locomotive, independent of the regular throttle and connections to the steam chests when the said throttle is closed and the locomotive is moving either by its momentum or down grade to overcome the vacuum in the cylinder and steam chests caused by the reciprocating movement of the cylinder pistons and steam chest valves and thus prevent the ingress of air and smoke box fluids and solids, which destroy the lubrication in the cylinders and steam chests.

In order to accomplish the desired result use is made of a drifting valve connected with the steam chests and with the boiler to supply saturated steam to the steam chests, the valve being provided with an automatic shut-off to close the valve automatically when the steam in the steam chests reaches a predetermined pressure. Use is also made of a control valve under the control of the engineer and connected with the drifting valve to render the drifting valve wholly inoperative thus preventing accidental admission of the steam into the steam chests by way of the drifting valve.

A practical embodiment of the invention is represented in the accompanying drawings forming a part of this specification, in which similar characters of reference indicate corresponding parts in all the views.

Figure 1 is a side elevation of the drifting valve device as applied to a locomotive shown in dotted lines;

Fig. 2 is a plan view of the same;

Fig. 3 is an enlarged sectional side elevation of the drifting valve with parts shown in elevation;

Fig. 4 is a vertical transverse section through a portion of the drifting valve at one side of its center.

Fig. 5 is a sectional plan view of a part of the same; and

Fig. 6 is a plan view of the drifting valve with a portion of the cap removed.

Since the superheater for locomotives has been perfected so that the steam is superheated to a high degree before it is admitted into the steam chests and cylinders, it has been concluded that by the use of superheated steam, the walls and surfaces of the steam chests and cylinders become heated to such a degree that if air containing oxygen is admitted into the steam chests and cylinders, the lubricating oil on said walls and surfaces will be carbonized or burned and thus the lubrication destroyed and the surfaces which slide on each other are left dry and very rapidly wear themselves away. Besides the destruction of the lubrication by the admission of air, there are other substances which must be kept out of the steam chests and cylinders. These are the hot gases and solids from the smoke-box. Unless there is sufficient pressure in the steam chests to be admitted into the cylinders, there is danger that as the pistons move in the cylinders a vacuum (pressure below the pressure in the smoke-box) will be formed whereby when the steam chest valves open the communication to the exhaust, there will be an inflow of smoke-box fluids and solids into the steam chests and cylinders. This would obviously assist in the rapid destruction of all the wearing parts in connection with the steam chests and cylinders, which include steam chest valve stems and packing, valves and bushings, cylinder pistons and bushings, piston rods and packing.

At present, it is the practice on some railroads, with locomotives not equipped with special devices for drifting purposes, to have the engine-man open the steam throttle slightly and furnish the cylinders with steam through the same course when the engine is drifting as when the engine is working. This method has the disadvantage of necessitating the use of superheated steam which is not as lubricative as saturated steam and also the human element of not being able to admit the exact amount of steam required to produce the desired economical results. If too much steam is furnished, there will be a waste of steam and an excess draft on the fire which will consume coal unnecessarily, and if not enough steam is furnished, the troubles, as stated above, will not be overcome. By the improved drifting valve device presently to be described in detail the above-mentioned objections are overcome.

The locomotive illustrated in dotted lines in Figs. 1 and 2 and on which the drifting valve device is shown applied is provided with the usual boiler 10, smoke-box 11, 5 throttle valve 12 controlled by the lever 13 within reach of the engineer in the cab of the locomotive. When the throttle valve 12 is opened, steam is admitted into the dry pipe 14 from which the steam passes through 10 the superheater 15 to the steam pipes 16 connected with the steam chests 17 of the cylinders 18.

The drifting valve 19 is shown located within a small dome 20 arranged on the 15 top of the boiler 10 near the front end thereof, and the drifting valve 19 is provided with a supply pipe 21 extending backward and opening into the steam dome 22 of the boiler 10 and within which steam dome is 20 located the throttle valve 12 before mentioned. The drifting valve 19 is provided on opposite sides with steam delivery pipes 23 connected with T-fittings 24 attached to the steam chests 17 to supply the latter with 25 saturated steam, as hereinafter more fully explained. It will be noticed that by the arrangement described, a steam passage is provided for the steam chests 17 wholly independent of the steam passage for operating the pistons in the cylinders 18, in 30 the usual manner.

Within the cab of the locomotive is arranged the usual turret 25 for supplying steam to operate the accessories of the locomotive, and this turret 25 is connected by a pipe 26 with the drifting valve 19, and this pipe 26 is provided with a three-way valve 27 for controlling the drifting valve 19 the normal position of which sustains 40 the drifting valve in operative condition. When this valve is closed and pipe 26 thereby cut off the drifting valve is rendered wholly inoperative. The valve 27 is provided with an outlet 28 connecting the drifting valve 19 with the outlet 28 to relieve the drifting valve of steam pressure, as hereinafter more fully explained. The pipe 26 intermediate the valve 27 and the turret 25 is provided with a shut-off valve 29 for 45 completely disconnecting the pipe 26 from the turret 25 when the engine is laid up for any length of time in cold weather or for other reasons.

The drifting valve 19 is constructed in 55 detail as follows, special reference being had to Figs. 3, 4, 5 and 6: The valve body 30 of the drifting valve 19 is provided with a base 31 and a cap 32, the body and base being fastened together by bolts 33, and the 60 body and cap being fastened together by bolts 34. The base 31 is provided with a flange 35 seated on a ring 36 seated on the boiler shell 39. The flange 35 is fastened to the boiler shell 39 by stud bolts 37 to 65 securely hold the drifting valve in position

on the boiler shell. The steam supply pipe 21 previously mentioned screws in the ring 36 and delivers steam into a chamber 40 formed in the base 31. This chamber 40 is connected by a passage 41 with the cap 70 32, the passage extending through the base 31 and the body 30, as plainly indicated in Fig. 4. Within the cap 32 is centrally arranged a valve 42 adapted to be seated on a valve seat 43 interposed between the body 75 30 and the cap 32 and held in place by the bolts 34. The top of the valve 42 is pressed on by one end of a coil spring 44 abutting with its other end against the cap 32 to normally hold the valve 42 to its seat 43. 80 The valve 42 is provided at its under side with a central polygonal recess 45 into which projects the correspondingly shaped upper end 46 of a bolt 47 having a collar 48 abutting against the under side of a 85 threaded boss 50 forming an integral part of the valve 42 at the under side thereof. On the boss 50 screws a coupling 51 having an inwardly extending flange 52 engaging the under side of the collar 48. The bolt 47 is 90 engaged by a hub 53 of a piston 54 mounted to reciprocate in a cylinder 55 formed centrally in the valve body 30, and the said hub 53 extends through a reduced bearing 56 into a cylinder 57 formed in the base 31 95 and containing a piston 58 fastened to the hub 53 by a nut 59 screwing on the lower end of the bolt 47. By the arrangement described, the valve 42 and the pistons 54 and 58 are connected with each other to move in 100 unison. By reference to Fig. 3, it will be seen that the steam delivery pipes 23 lead from the valve body 30 at a point intermediate the valve seat 43 and the upper end of the cylinder 55 so that when the valve 42 105 is open steam can pass by way of the passage 41, cap 32 and valve seat 43 into the chamber 60 connected with the upper end of the cylinder 55 and from which lead the delivery pipes 23. The bottom of the cylinder 55 is provided with a port 61 opening to the atmosphere so that the under side of the piston 54 is exposed to atmospheric pressure. 110

The pipe 26 previously mentioned opens 115 into the lower end of the cylinder 57 so that when the engineer opens the valve 27 steam under boiler pressure passes into the cylinder 57 and acts against the under side of the piston 58 to move the latter upward and with it the piston 54 and the valve 42 to lift the latter off its seat 43. When this takes place saturated steam passes through the pipe 21, passage 41, valve seat 43, chamber 60 and pipes 23 into the steam chest 17 120 to supply the latter with saturated steam under reduced pressure during the time the locomotive is drifting.

The lower face of piston 58 has an exposed area greater than the upper face of the 130

valve 42, so that upon accumulation of pressure through pipe 26 below the piston 58, the pressure above the valve 42 and also the pressure of the spring 44 will be overcome. 5 The piston 54 serves as a balancing piston while the piston 58 serves as an opening and closing piston for the valve 42. It is understood that owing to the fact that the piston 58 has an exposed lower face slightly larger 10 than the valve 42 the extra pressure due to the larger area causes an upward movement of the entire piston valve to lift the valve 42 off its seat 43, as previously explained. When the valve 27 is closed and steam is 15 shut off from the cylinder 57 then the piston valve returns to its normal position aided by the action of the spring 44. It is thus obvious that, in operation, the pressure in the chamber 60 acts on equal surfaces on the under- 20 side of valve 42 and the upper side of piston 54, and will, therefore, have no effect or influence in the opening or closing of valve 42. Then, as boiler pressure is exerted on the top of valve 42 and against the lower face of 25 piston 58, valve 42 will be forced open, because, as before stated, the exposed face of piston 58 is slightly larger than that of valve 42. The valve can only be closed by a pressure on the top side of piston 58 through 30 pipes 70, and when this pressure is reduced, the extra force against the lower face of piston 58 as compared to that on the top side of valve 42, including spring 44, will cause an upward opening movement of valve 35 42, even against some pressure on the top side of the piston 58. Thus the valve 42 will be opened while there is yet some pressure in the pipe 16 and steam chests 17. Since all 40 of these pressures are gage pressures, that is, above atmospheric, the pressure on the underside of piston 54 will have no effect upon the movement of the parts and need not therefore be further considered.

The upper end of the cylinder 57 is connected by a small pipe 70 with one of the pipes 16 (see Figs. 2 and 3) so that in case the pressure in the pipe 16 exceeds the pressure to which the valve is set the piston 58 is forced downward to close the valve 42 at 45 the time the valve 27 is open. Thus if there is an excess of pressure in the pipe 16 beyond that for which the drifting valve has been set then the valve 42 closes automatically and remains closed until the pressure in the pipe 16 falls below the predetermined pressure to which the drifting valve has been 50 set. It is understood that by this arrangement soot or other extraneous matter in the smoke-box 11 cannot be sucked into the engine cylinders as the pressure in the latter is always slightly higher than that in the smoke-box 11. It is also understood that the spring 44 holds the valve 42 to its seat when the pressure is shut off so that the locomotive can be readily started up after hav-

ing been laid up, without danger of steam leaking past the valve seat 43 in case the valve 42 should be open. It is further understood that the predetermined pressure to which the valve 19 is set is not sufficient 70 to start the locomotive on a level track.

In order to allow a mechanic to regrind the valve 42 in its seat 43, said valve is provided on top with a centrally located polygonal boss 80 adapted to be engaged by a 75 correspondingly shaped socket 81 formed in the lower end of a spindle 82 extending through a stuffing box 83 arranged on top of the cap 32. The outer end 84 of the spindle 82 is made polygonal for the application of 80 a wrench or other suitable tool with which to move the spindle 82 downward to engage the socket 81 with the boss 80 and to allow of turning the spindle so as to rotate the valve 42 on its seat 43 thus grinding the 85 valve in its seat. After the grinding operation is repeated the spindle 82 is returned to its upper normal position, as shown in Fig. 3, to allow free opening of the valve 42 as previously explained. 90

In order to supply a lubricant to the steam chests 17 the following arrangement is made: In the cab of the locomotive is arranged the usual lubricator 90 connected to the turret 25 by a steam supply pipe 91 having a valve 95 92. From the lubricator 90 lead pipes 93 connected by chokes 94 with the T-fittings 24 to supply lubricant to the steam chests 17.

It will be noticed that by this arrangement the oil feed is entirely independent of 100 the drifting valve and therefore does not influence the latter's action.

From the foregoing it will be seen that the controlling valve 27 is within convenient reach of the engineer and hence enables the 105 latter to control the drifting valve system.

By locating the drifting valve 19 on the top of the boiler, all pipes connected therewith readily drain off all water of condensation and hence such pipes are not liable to 110 burst owing to freezing of the water during cold weather. It will also be noticed that the pressure for closing the valve 42 is from the top thereof and the steam has a chance to expand before acting on the valve to close 115 it and hence the valve is not liable to flutter. In the arrangement described, the control pipe is connected to obtain the pressure for controlling the opening and closing of the valve after the steam has expanded to steam 120 chest pressure.

The operation of the valve is as follows:

Consider the locomotive standing still, with the throttle valve closed and no steam in the steam chests. The boiler contains 125 steam under pressure and the locomotive is equipped with the drifting valve device. The device being connected with the boiler, the steam exerts a pressure on the top of valve 42, holding it on its seat 43. By means 130

of valve 27 and pipe 26, connect the lower side of piston 58 with the boiler pressure. Because piston 58 is slightly larger than valve 42, the latter is raised from its seat 5 admitting steam into the steam chests 17 through pipes 23. It must here be noted that the pressure in the chamber 60 has but little effect in causing any movement of the pistons 54 and 58 and valve 42, because piston 54 10 balances the pressure on the under side of valve 42. The steam which is admitted into the steam chests enters steam pipe 16 and thence into pipe 70 which connects with the upper side of piston 58. Because nearly the whole upper area of piston 58 is acted upon by steam chest pressure, it will require only a much lower pressure than that in the boiler, as predetermined in the design of pistons 54 15 and 58 and valve 42, to force valve 42 back down on its seat 43 and thus shut off the admission of any more steam into the steam chests to increase the pressure. Thus the valve is a pressure-reducing valve, as the pressure in the steam chests is kept reduced 20 to the predetermined amount. If steam is allowed to escape or is used from the steam chests thus lowering the pressure in the steam chests, the pressure on the top of piston 58 is correspondingly lowered and the boiler pressure acting on the bottom of piston 58 will be again permitted to lift valve 42 from its seat 43 admitting steam to the steam chests to replace the steam that was 25 drawn away, but the connection to the top of piston 58 will not permit of the pressure being increased above the predetermined amount.

Having thus described my invention, I 40 claim as new and desire to secure by Letters Patent:

1. A drifting valve device for locomotives, comprising a pressure reducing valve having a connection with the steam chests of the 45 locomotive and having a connection with the steam compartment of the boiler to admit saturated steam under reduced pressure to the said steam chests, the said pressure reducing valve having means to close it automatically when the steam in the steam chests reaches a predetermined pressure, a controlling valve under the control of the engineer and connected with the boiler and with the 50 said pressure reducing valve at the high pressure side thereof to render the same operative and inoperative, the controlling valve having an outlet for relieving the drifting valve of steam pressure.

2. A drifting valve device for locomotives, comprising a pressure reducing valve 60 having a valve body furnished with an inlet and an outlet connected to the locomotive cylinder and a valve seat intermediate the said outlet and inlet, a spring pressed valve 65 controlling the said valve seat and having

two pistons of which one is exposed at its under face to the atmosphere and at its upper face to the pressure of the steam in the outlet, a manually controlled valve connected with the locomotive boiler to admit 70 steam to the underside of the other piston, and a connection whereby pressure from the cylinder supply is admitted thereto, leading into the valve body above the said last mentioned piston. 75

3. A drifting valve device for locomotives, comprising a pressure reducing valve having a valve body furnished with an inlet, an outlet and a valve seat intermediate the said inlet and outlet, a spring pressed valve 80 controlling the said valve seat and having two pistons of which one is exposed at its under face to the atmosphere and at its upper face to the pressure of the steam in the outlet, a manually controlled valve 85 connected with the locomotive boiler to admit steam to the underside of the other piston, and a steam connection between the steam chest of the engine and the upper side of the said second piston. 90

4. A drifting valve device for locomotives, comprising a pressure reducing valve having an inlet, an outlet and a valve seat intermediate the said inlet and outlet, a spring pressed valve coöperating with the 95 said seat and having a piston connected therewith and exposed upon one side to the pressure of the locomotive steam chest, a second piston connected to the valve and exposed to the pressure of steam in the outlet, 100 a connection between the said inlet and the steam compartment of the locomotive boiler, a connection between the said outlet and the steam chest of the locomotive engine, and a manually controlled valve connected with 105 the locomotive boiler and the said valve body to admit boiler pressure to the other face of the first piston.

5. A drifting valve device for locomotives, comprising a pressure reducing valve 110 having an inlet, an outlet and a valve seat intermediate the said inlet and outlet, and a spring pressed valve controlling the said seat to connect the inlet with the said outlet, the said valve having two spaced pistons of 115 which the upper face of one piston is exposed to the steam pressure in the outlet and its under face exposed to the atmosphere, a manually controlled valve connected with the boiler and the said valve body for admitting boiler pressure to the underside of the other piston, and a connection between the steam chest and the said valve body to admit steam chest pressure to the upper side of the said other piston. 120

6. A drifting valve device for locomotives, comprising a pressure reducing valve having a saturated steam supply connection with the steam chests of the locomotive and having a connection with the steam com- 130

- partment of the boiler to admit saturated steam under reduced pressure to the said steam chests, the said pressure reducing valve having means to close it automatically 5 when the steam in the steam chest reaches a predetermined pressure, a controlling valve under the control of the engineer and connected with the boiler and with the said pressure reducing valve at the high pressure 10 side thereof to render the same operative and inoperative, and a connection between the reducing valve and the steam chests to which the valve is subject when said controlling valve is closed.
- 15 7. A drifting valve device for locomotives, comprising a pressure reducing valve having a valve body provided with a base and a cap, a passage connecting the base with the cap, a valve seat intermediate the cap and the top of the valve body, a steam supply pipe connected with the steam compartment of the boiler and with the said base, and the passage leading therefrom to the cap, a steam delivery pipe connecting the said valve body with the steam chest of the locomotive engine, a cylinder in the said valve body and connected at its underside
- 20 with the atmosphere and at its upper end with the said valve seat and the said delivery pipe, a cylinder in the said base, a 30 spring pressed valve in the said cap and adapted to be seated on the said seat, a double piston connected with the said valve, one of the pistons being a balancing piston and extending in the said body cylinder and 35 the other being an opening and closing piston extending in the said base cylinder, a steam pipe connected with the underside of the said base cylinder and connected with the boiler, a three way valve in the said 40 steam pipe and under the control of the engineer to connect the said steam pipe with the said base cylinder or the latter with the atmosphere, and a pipe connecting the upper end of the said base cylinder with the steam 45 chest.

In testimony whereof I have signed my name to this specification in the presence of two subscribing witnesses.
